Primary Examiner — Ricky Pham(74) *Attorney, Agent, or Firm* — Barnes & Thornburg LLP**(57) CLAIM**

The ornamental design for a reclined swing, as shown and described.

DESCRIPTION

FIG. 1 is a perspective view of a reclined swing assembly showing my new design;

FIG. 2 is a front elevation view of the reclined swing assembly of FIG. 1;

FIG. 3 is a rear elevation view of the reclined swing assembly of FIG. 1;

FIG. 4 is a side view of the reclined swing assembly of FIG. 1, the other side view of this reclined swing assembly would be a mirror image of this view;

FIG. 5 is a top view of the reclined swing assembly of FIG. 1; and,

FIG. 6 is an underside view of the reclined swing assembly of FIG. 1.

Note that the dashed lines shown in these drawings do not form part of the claimed invention.
